UNITED STATES PATENT OFFICE.

ARTHUR E. TRUESDELL, OF PITTSFIELD, MASSACHUSETTS.

LIME KILN WITH PYROMETER MECHANISM.

Application filed January 15, 1926. Serial No. 81,418.

This invention relates to lime kilns and the like and particularly to those kilns which employ a pyrometer mechanism for determining the temperature in the stack. To get a proper reading of the pyrometer it is necessary to insert the end thereof into the interior of the stack for a distance of six inches or more but if the pyrometer remains in this position when the lime or other material is being withdrawn from the bottom of the stack there is every likelihood that the pyrometer will be broken by the downward movement of the material in the stack.

It is one of the objects of my present invention to provide novel means to indicate that the pyrometer is in operative position whenever an attempt is made to withdraw lime from the bottom of the stack at a time when the pyrometer is thus positioned.

A lime kiln is usually provided at its lower end with a hopper in which the burnt lime accumulates and the hopper is provided with a closure, usually in the form of so-called shears, which may be opened whenever the burnt lime is to be withdrawn.

In the preferred embodiment of my invention I have provided means associated with the shears which will operate to give an indication whenever an attempt is made to open the shears while the pyrometer is in its operative position. The indications may be either in the nature of a signal, either audible or visual, which will be given whenever an attempt is made to open the shears while the pyrometer is in its operative position or may be in the nature of a lock device which will lock the shears from opening when the pyrometer is in such position. Where the lock form of indication is employed I will preferably so construct the lock that so long as the pyrometer is in its operative position within the kiln the shears will be locked and will be released only when the pyrometer is withdrawn from the kiln chamber.

Furthermore the indicating means, whether in the form of a signal or a lock for the shears, is preferably so constructed that it may be used for locking the pyrometer in its withdrawn position, the indicating device at this time being held inoperative so that the material may be freely withdrawn from the stack without giving any signal indication. When, however, the pyrometer is introduced into the stack for the purpose

of obtaining a pyrometer reading then the signal will be operative to give indication in case an attempt is made to withdraw material from the stack.

In order to give an understanding of my invention I have illustrated in the drawings some selected embodiments thereof which will now be described after which the novel features will be pointed out in the appended claims.

Fig. 1 is a view in elevation of a vertical kiln embodying my invention;

Fig. 2 is a section on the line 2—2, Fig. 1 showing the shears for closing the hopper;

Fig. 3 is an enlarged section on the line 3—3, Fig. 2;

Fig. 4 is a fragmentary view in elevation showing a different embodiment of the invention;

Fig. 5 is a fragmentary sectional view showing the details of the three-way valve used in Fig. 4;

Fig. 6 is a view in elevation showing a different embodiment of the invention;

Fig. 7 is a fragmentary view in elevation showing the device illustrated in Fig. 1 but with the pyrometer in its operative position for taking the reading;

Fig. 8 is a fragmentary sectional view of the switch used in the device shown in Fig. 6;

Fig. 9 is a diagrammatic view illustrating a different embodiment of the invention.

Referring first to Fig. 1, 1 designates the stack of a kiln which is provided with the usual chamber 2 in which the limestone to be burned is placed. 3 indicates the usual furnace employed in connection with the burning of the lime and 4 is the hopper at the bottom of the stack in which the burnt lime accumulates.

The hopper is open at the bottom and is provided with a closure for closing the opening, which closure may be removed to permit the burnt lime to be discharged from the hopper. The closure herein shown is in the form of the familiar flat shears which is commonly used in lime kilns of this nature. These flat shears comprise the two plate members 5 which are pivoted at 6. Each member is provided with a handle 7 by which it may be manipulated. When the handles are separated from each other the closure plates 5 will be similarly separated thus providing an opening in the bottom of

the hopper through which the burnt lime may be discharged. By closing the plates together the opening is closed.

These parts are or may be all as usual in 5 kilns of this type and form no part of my present invention.

8 indicates a pyrometer of any appropriate type by means of which the temperature of the lime in the chamber 2 may be ascertained 10 while the kiln is in operation. This pyrometer extends through an opening 9 in the wall of the kiln and when it is functioning to give a temperature indication the inner end 10 thereof will be projected 15 into the chamber 2 for an appropriate distance.

For practical operation the best position in which to utilize the pyrometer is at about the point shown, that is, at a point above 20 the furnace, but this point is entirely out of reach of a person standing on the firing floor 60 from which the furnace is fired. I have, therefore, provided means for operating 25 the pyrometer which is accessible from the firing floor 60. This means consists of a lever 11 pivoted at 12 to the stack and connected to the outer end of the pyrometer so that on the swinging of the lever toward the kiln from the full to the dotted line 30 position, Fig. 6, or into the position shown in Fig. 7 the pyrometer will be placed in its operative position with the end 10 situated within the kiln chamber and in appropriate position to secure the pyrometer reading. 35 The lower end of the lever 12 is provided with a handle 13 by which it may be manipulated and this handle is situated within convenient reach of a person on the firing floor 60. With the above described means the 40 pyrometer may be projected into the kiln as shown in Fig. 7 or withdrawn from the kiln as shown in Figs. 1 and 6, while the kiln is in operation.

In addition to this feature relating to the 45 means for operating the pyrometer my invention also includes means which is operative to give an indication whenever an attempt is made to open the shears at a time when the pyrometer is in its operative position shown in Fig. 7. As stated above this indication may be in the nature of a signal which will be given under these circumstances or may be in the nature of a device to lock the shears from being opened under 55 similar circumstances. In the case of the lock the device will operate to prevent any lime from being withdrawn from the hopper while the pyrometer is in its operative position, the shears being released and being free 60 to be opened when the pyrometer is withdrawn from the kiln as shown in Fig. 1.

Figs. 1 to 8 of the drawings show embodiments of the invention in which the indicating device is in the form of a means for 65 locking the shears from being opened at a

time when the pyrometer is in its operative position and these figures also show means for locking the pyrometer in its withdrawn position when the shears are unlocked so that there is an interlocking connection between 70 the pyrometer and shears which will prevent the pyrometer from being inserted when the shears are unlocked and conversely will prevent the shears from being opened when the pyrometer is in its operative position. 75

One interlocking mechanism operating in this way is shown in Fig. 1. The lock for the shears comprises a locking member 14 having two projections 15 adapted to embrace the two handles 7 of the shears as 80 shown in dotted lines Fig. 3, and when so embracing the handles preventing them from being separated. In Fig. 1 this locking member is carried by a lever 16 pivoted at 17 and the end of the lever is connected 85 by a link 18 to a locking arm 19 pivoted to the kiln at 20.

21 indicates a collar or shoulder on the pyrometer-actuating lever 11 and which cooperates with the locking arm 19 to hold the 90 lock 14 in inoperative position.

The weight of the link 18 and locking arm 19 is such that when the locking arm is released the weight thereof together with that of the link 18 will overbalance the lock 95 14 and will raise the latter into its operative position shown in dotted lines Fig. 3. The shears lock 14 is held inoperative when the pyrometer is withdrawn by the engagement of the end of the locking arm 19 with the 100 collar 21 as shown in Fig. 1. When the parts are in this position the end of the arm 19 resting on the collar 21 will hold the shears lock 14 released and the engagement of the lever 11 with the end of the 105 arm 19 will hold the pyrometer withdrawn. The material may, therefore, be freely withdrawn from the hopper without danger of 110 injuring the pyrometer as the latter is locked in its withdrawn position.

When it is desired to take a pyrometer reading the operator will first pull the lever 11 backwardly sufficiently to release the arm 19 from the collar 21 and when this occurs the weight of the arm 19 and the link 18 will overbalance that of the lock 14 so that the latter will be raised into the position shown in Fig. 7 and in dotted lines Fig. 3, thus locking the shears, the arm 19 at this time dropping into a vertical position shown 115 in Fig. 7. After the shears have been thus locked the lever 11 is free to be swung inwardly as shown in Fig. 7 thus projecting the inner end 10 of the pyrometer into the kiln chamber. The shears, being at this 120 time locked, no material can be withdrawn from the kiln and, therefore, the pyrometer is relieved of any danger of being broken by downward movement of the material into 125 the hopper. 130

After the pyrometer reading has been taken the pyrometer may be withdrawn by swinging the lever 11 outwardly after which the shears may be unlocked by raising the locking arm 19 and again engaging the arm with the collar 21 on the lower end of the lever 11 thus locking the pyrometer in its withdrawn position and also maintaining the shears lock inoperative.

It will thus be seen that with the device shown in Fig. 1 the pyrometer cannot be introduced into the kiln except when the hopper shears are locked and the pyrometer will be locked in its withdrawn position so long as the shears remain unlocked. The locking of the shears serves as an indication that the pyrometer is in its operative position.

In Fig. 4 I have illustrated a little different embodiment of the invention. In this device the lock for the shears is pneumatically or hydraulically operated. The lock, which is indicated at 14, is carried by an arm 22 pivoted at 23, said arm having rigid therewith an upstanding arm 24 to the upper end of which is connected a piston operating in a cylinder 25. 26 is a pipe leading to the cylinder and through which motive fluid under pressure is introduced into the cylinder 25. This pipe has a three-way valve 27 therein which is controlled by an arm 28 similar to the locking arm 19 in Fig. 1.

The three-way valve 27 has a supply pipe 51 leading thereto and an exhaust port 52. The valve is of the plug valve type having a port 53 which upon turning of the plug establishes a communication between the supply pipe 51 and the pipe 26 leading to the cylinder or between the pipe 26 and the exhaust port 52. Normally when the shears are unlocked, as shown in Fig. 4, the cylinder will be exhausted, this being the condition when the valve is in the position shown in Fig. 5, thus establishing a communication between the pipe 26 and the exhaust 52. When the valve is in this position the arm 28 thereof rests on the collar 21, said collar locking the arm in this position and the arm locking the lever 11 withdrawn.

When it is desired to use the pyrometer the arm 11 is pulled backwardly a sufficient distance to release the arm 28 from the collar 21 and the arm 28 may then be swung downwardly thus turning the valve so that the port 53 will connect the supply pipe 51 and the pipe 26. This will allow motive fluid to flow into the cylinder 25 and will move the piston to the right thereby raising the shears lock 14 and locking the shears.

After the pyrometer reading has been taken the pyrometer is withdrawn by swinging the lever 11 backwardly and then the valve arm 28 is restored to the position shown in Fig. 4, in which position it is held by the collar 21 and in which position it locks the lever 11 from swinging inwardly.

This moves the valve into the position shown in Fig. 5 and thus exhausts the cylinder and allows the shears lock to drop into its inoperative position by the weight thereof.

In Fig. 6 I have shown a different embodiment of the invention in which the interlocking is in the nature of an electrical device. In this embodiment the lock 14 for the shears is carried by an arm 29 pivoted at 30 and having integral therewith an upstanding portion 31, the upper end 32 of which is in the form of the armature for a magnet 33. The circuit 34 of the magnet, which includes a suitable source of electrical supply 35, has therein two contacts 36 and 39 which are enclosed in a casing 58 preferably of insulating material. The contact 39 is a resilient contact and its resiliency will normally hold it in engagement with the contact 36 thus closing the circuit 34. When the switch is opened by separation of the contacts the magnet 33 is de-energized and the shears lock 14 will drop by gravity into its inoperative position. When the circuit is closed, however, and the magnet 33 is energized the armature 32 will be attracted to the magnet thus raising the shears lock 14 into its operative position and locking the shears closed.

Means are provided whereby the contacts 39 and 36 will be held separated thus opening the circuit so long as the pyrometer is withdrawn but will be brought into contact thus closing the circuit when the pyrometer is inserted into the kiln.

The lever 11 has pivotally connected to its lower end a member 38, the end of which is adapted to enter an opening 59 in the casing 58 and to engage the projecting end of the resilient contact 39. When the parts are in this position, as shown in Figs. 6 and 8, the weight of the lever 11 is sufficient to hold the contacts separated and the circuit open.

When it is desired to take a pyrometer reading the lever 11 is pulled backwardly sufficiently to withdraw the arm 38 from the casing 58 thus allowing the contacts to close by the resiliency of the contact 39. The closing of the contacts will energize the magnet 33 and thus cause the shears lock 14 to be moved into its operative position. When the arm 38 has been thus withdrawn from the switch casing 58 it will drop into the dotted line position Fig. 6 and the lever 11 may then be swung inwardly into its dotted line position thus projecting the pyrometer into the kiln chamber. When the pyrometer reading has been taken the lever 11 is pulled backwardly to withdraw the pyrometer from the kiln chamber and the lever is held in such position by re-inserting the end of the arm 38 into the switch casing 58 as shown in Fig. 8 thereby opening the circuit and releasing the shears lock. With

this embodiment also the shears will be locked before the pyrometer is moved into the kiln and the pyrometer is held withdrawn from the kiln so long as the shears are unlocked.

Furthermore, in this and the embodiment shown in Fig. 4, the locking of the shears constitutes an indication that the pyrometer is in its operative position.

- 10 Instead of an indication in which the shears are locked when the pyrometer is in its operative position I may employ an indication in the form of a signal which will give this information. Such a signal may 15 be either an audible signal or a visual signal and may be constructed so that if an attempt is made to open the shears at a time when the pyrometer is in its operative position as shown in Fig. 7 the audible or visual signal 20 will be given to apprise the operator that the pyrometer is in its operative position and hence would be liable to be injured if material is withdrawn from the kiln.

In Fig. 9 I have illustrated an embodiment of the invention having this signal indication. In this construction the end 6 of each shear member is provided with a contact 62, said contacts so arranged that they 25 will be closed whenever the shears are 30 opened. These contacts 62 are in a circuit 63 having a signal 64 therein and also having two contacts 36 and 39 similar to the contacts shown in Fig. 8 and which are held open by an arm 38 on the pyrometer-operating lever 11 when the pyrometer is retained 35 in its withdrawn position. So long as the pyrometer is in its withdrawn position and the circuit 63 is open at the contacts 36, 38 then, of course, the closing of the contacts 40 62 by the opening of the shears will have no effect in operating the signal 64. If, however, the pyrometer is placed in its operative position as shown in Fig. 7 and in dotted lines Fig. 6 in which case the arm 38 has 45 been withdrawn from the switch casing 58 and the circuit is closed at the contacts 36, 39, then if an attempt is made to open the shears to withdraw the lime from the hopper the contacts 62 will be closed thus closing the 50 signal circuit and operating the signal 64. The operation of the signal 64, whether it be a visual signal or an audible signal will give information to the operator that the pyrometer is in its operative position and 55 will thus prevent him from proceeding to withdraw lime from the hopper in ignorance of the fact that the pyrometer is projecting into the kiln chamber.

I claim.

- 60 1. The combination with a stack kiln having a chamber in which material is burned, said kiln being provided with an opening through which the burnt material is discharged and a closure for said opening, of 65 a pyrometer, actuating means for project-

ing the pyrometer into the chamber of the stack or withdrawing it therefrom while the kiln is in operation, and means controlled by the pyrometer-actuating means to indicate whether the pyrometer is projected into 70 the stack or not.

2. The combination with a stack kiln having a chamber in which material is burned, said kiln being provided with an opening 75 through which the burnt material is discharged and a closure for said opening, of a pyrometer, means for projecting the pyrometer into the chamber of the stack or withdrawing it therefrom while the kiln is in operation, and means controlled by the 80 pyrometer-moving means to give an indication when an attempt is made to open the closure at a time when the pyrometer is in its operative position.

3. The combination with a stack kiln having a chamber in which material is burned and also having a hopper in which the burnt material accumulates, of a pyrometer 90 adapted to be projected into the chamber of the stack or withdrawn therefrom while the kiln is in operation, a closure for the hopper, and means rendered operative when the pyrometer is projected into the kiln chamber to prevent the closure from being 95 opened.

4. The combination with a stack kiln having a chamber in which material is burned and also having a hopper in which the burnt material accumulates, of a closure for the hopper, a pyrometer adapted to be projected into the chamber of the stack or withdrawn therefrom while the kiln is in operation, a lock for locking the closure in closed position, and means to render the lock operative when the pyrometer is projected into 100 the stack chamber.

5. The combination with a stack kiln having a stack chamber in which material is burned and also having a hopper in which the burnt material accumulates, of a pyrometer 110 adapted to be projected into the stack chamber or withdrawn therefrom, a closure for the hopper, a lock for the closure, and means to lock the pyrometer in its withdrawn relation when the closure is unlocked.

6. The combination with a stack kiln having a stack chamber in which material is burned and also having a hopper in which burnt material accumulates, of a closure for the hopper, a pyrometer adapted to be projected into the stack chamber or withdrawn therefrom, means for holding the pyrometer in its withdrawn relation, and means to indicate when an attempt is made to open the closure at a time when the pyrometer is released from its withdrawn position.

7. In a kiln, the combination with a stack having a chamber, of a firing floor, a pyrometer adapted to be projected into the kiln chamber at a point considerably above 120

- the firing floor, a lever pivoted to the stack and connected to the pyrometer and extending to within reach of an operator on the firing floor, whereby the pyrometer may be withdrawn from or projected into the stack chamber by swinging movement of the lever. 5 cumulates, said hopper having an opening through which material is discharged, a closure for said opening, a pyrometer adapted to be projected into operative position in the stack chamber to indicate the temperature therein or to be withdrawn from the chamber, actuating means for placing the pyrometer in either of these positions, means for holding the pyrometer in its withdrawn position, a lock for the closure, and means for rendering the lock operative when the pyrometer is in its operative 45 position and inoperative when the pyrometer is held in its withdrawn position.
8. In a kiln, the combination with a stack having a chamber, of a firing floor, a pyrometer adapted to be projected into said chamber at a point considerably above the firing floor, a lever pivoted to the stack and connected to the pyrometer and extending to within reach of an operator on the firing floor, whereby the pyrometer may be withdrawn 10 from or projected into the kiln chamber by swinging movement of the lever, and means to retain the lever in the position it occupies when the pyrometer is in withdrawn position. 15
9. In a stack kiln, the combination with a stack chamber in which material is burned, of a hopper in which the burnt material accumulates, a closure for the hopper which may be opened to permit discharge of material therefrom, a pyrometer adapted to be projected into the stack chamber or withdrawn therefrom, a lock for locking the closure in closed relation, and means to render the lock operative when the pyrometer 20 is projected into the chamber. 25
10. In a stack kiln, the combination with a stack chamber in which material is burned, of a hopper in which the burnt material ac- 30
